UNITED STATES PATENT OFFICE.

OSCAR P. McGEE, OF DALLAS, TEXAS, ASSIGNOR OF ONE-HALF TO WILLIAM A. SEDWICK, OF DALLAS, TEXAS.

ELEVATOR-DOOR-OPERATING EQUIPMENT.

Application filed October 23, 1926. Serial No. 143,591.

This invention relates to new and useful improvements in elevator door operating equipments.

The object of the invention is to provide 5 certain improvements in and additions to the apparatuses illustrated in my Letters Patent No. 1,568,461, issued January 5, 1926, and my co-pending application filed February 4, 1926, Serial No. 85,875.

10 A particular object of the invention is to produce an apparatus which will be substantially noiseless in its operation and whereby the floor switches of my co-pending application will be eliminated.

15 An important object of the invention is to simplify the construction as well as to refine it, whereby the apparatus will operate more efficiently and the maintenance will be reduced.

20 A further object of the invention is to provide air cushions or checks operated by the carriage at the ends of its stroke, whereby the opening and closing of the door is made substantially noiseless and the parts 25 are saved from undue vibration incidental to an abrupt stop.

Another object of the invention is to provide, in conjunction with the door engaging 30 latch, an auxiliary closing means, whereby a full closing of the door is assured in addition to the travel of the carriage.

A still further object of the invention is to improve the controlling switches, whereby more positive contacts will be had.

35 Another important object of the invention is the provision of a master switch in combination with a cutout switch, thus providing a normally open door-operating circuit which can only be closed when the floor 40 of the elevator car is within a predetermined distance of the floor landing.

Another object of the invention is to provide a substantially noiseless suspension for the motor and to connect the same with the 45 operating chain by a jointed shaft or other suitable connections, whereby the motor may be mounted on a remote part of the car, thus making for more quiet operation.

A construction designed to carry out the 50 invention will be hereinafter described, together with other features of the invention.

The invention will be more readily understood from a reading of the following specification and by reference to the accompany-

ing drawings, in which an example of the invention is shown and wherein:

Fig. 1 is an elevation of a door operating apparatus constructed in accordance with my invention, the motor being omitted, 60

Fig. 2 is a plan view of the same,

Fig. 3 is an enlarged elevation of the carriage and component parts,

Fig. 4 is an end elevation of the same, the track and angle bar being in section, 65

Fig. 5 is a plan view of the same,

Fig. 6 is a rear elevation of the same,

Fig. 7 is a side elevation of the motor and its hanger,

Fig. 8 is an end elevation of the same, 70

Fig. 9 is a plan view of the door latch and keeper,

Fig. 10 is an elevation of the same,

Fig. 11 is a cross-sectional view taken on the line 11—11 of Fig. 9, 75

Fig. 12 is a cross-sectional view taken on the line 12—12 of Fig. 9,

Fig. 13 is a view of the door reversing switch partially in section and partially in elevation,

Fig. 14 is an end view of the same,

Fig. 15 is a view of the door opening and car circuit switch partially in elevation and partially in section,

Fig. 16 is an end view of the same, 80

Fig. 17 is a view of the master switch and the cut-out switch, portions being shown in elevation and portions in section,

Fig. 18 is a similar view at right angles,

Fig. 19 is a cross-sectional view on the line 90 19—19 of Fig. 18,

Fig. 20 is a detail of the switch arm lever mechanism,

Fig. 21 is a diagrammatical view showing the electrical circuit,

Fig. 22 is an end elevation of the apparatus shown in Fig. 1, and

Fig. 23 is a sectional view of the friction clutch.

In the drawings the numeral 10 designates 100 a longitudinal track, which I prefer to make of fibre or some other noise reducing material. On its rear side the track is reinforced by a longitudinal T bar 11 made of metal, portions of the track being exposed above and below said bar. The track is suitably supported by arms 13 extending from standards 12 at each end of the apparatus as is shown in Figs. 1, 2, 4 and 22. The standards are suitably fastened on the 110

roof 14 of the elevator car. A bracket 15 secured to one of the standards supports a sprocket 16, while a bracket 17 mounted on the other standard 12 supports a drive shaft 18 on which a sprocket 19 is fastened. A sprocket chain 20 is supported by the sprockets.

A carriage 21 is connected to the upper run of the chain and is supported by flanged rollers 22 engaging the upper and lower edges of the track 10, as is best shown in Figs. 3, 4 and 6. In order to prevent injury to the driving parts in case the carriage should hang, the sprocket 19 is connected 15 to the shaft 18 by a friction clutch 23 of suitable construction, as is shown in Fig. 23.

At one end the carriage has an upright shoe wing 24 integral therewith. On the back of the plate of the carriage I provide 20 upper and lower slide rails 25 engaging in the hangers 26 of a slide 27. This slide carries a complementary shoe wing 28 formed integral therewith, as is shown in Figs. 3, 4 and 5. The wing 28 is slideable toward 25 and from the wing 24 to open and close the shoe.

For actuating the slide I provide a crank shaft 29 journaled in the carriage and extending transversely therethrough, as well 30 as extending through a slot 30 in the slide. A crank arm 31 fastened on the front end of the shaft contiguous to the face of the slide is pivoted to one end of a link 32 and has its opposite end journaled on a stud 33 35 mounted on the slide. By rocking the crank shaft, the arm 31 is swung up (dotted lines Fig. 3) and the link thus pulls the slide 27 and opens the shoe. The crank shaft 29 is actuated by a bell crank lever 34 secured to 40 its rear end and having arms 35 and 36 for adjustment into the path of a pin 37 mounted on the rear of the track 10, as is best shown in Figs. 4 and 6.

A coiled spring 38 has one end attached 45 to a stud 39 on the lever 34 midway between the arms thereof, while the lower end of the spring is attached to a bracket 40 mounted on the carriage. When the lever is swung the stud 39 will be carried to alternate 50 sides of the shaft 29, thus holding the lever in its adjusted position.

It is necessary to open and close the shoe because of its engagement with the door latches, one of which, 41, is shown in Figs. 9 55 to 12, inclusive. Each latch is right-angular in plan and has a bill 42 engaging with a bevel-ended keeper 43 adjustably held in a socket 44 by a set screw 45. An angular bracket 46 is secured to the top of the floor landing door 47. The latch includes an outwardly extending arm 48 which is mounted to swing in a channel arm 49 fastened to the bracket 46. The latch 41 is pivoted to the inner end of the arm 49 on a bolt 50. 60 A stud 51 on the inner end of the lever car-

ries a set screw 52 which engages the inner end of the arm 49 and limits the outward swing of the arm 48, as is shown in Figs. 9 and 12. A flat spring 53 interposed between the arms 48 and 49 tends to swing the latch. 70

The socket 44 is mounted on the end of a bracket 54 secured to the wall of the elevator shaft. This bracket, as is shown in Figs. 9 and 11, has an outwardly extending arm 55 on which a small roller 56 is journaled. A lever 57 is pivoted on the bolt 50 on top of the arm 49 and has a fork or yoke 58 engaging the roller 56. A coiled spring 59 has one end pivoted to a stud 60 on the arm 49, while its opposite end is pivoted to a stud 61 on the lever 57 located between the ends of the latter. The lever 57 has a lug 62 adapted to engage a pin 63 to limit the swing of the lever in one direction. 75

The function of the lever 57 is to assist 80 in closing the door. When the door is open and it approaches its closing position, the lever is in the position shown in dotted lines in Fig. 9, the stud 61 having been swung to the right of the pivot 50 and the lug 62 85 engaged with the pin 63 when the door was opened. As the door approaches its closing position, the yoke 58 is caused to straddle the roller 56 and as the bill 42 rides the bevel of the keeper 43, the lever 57 is swung 90 to the left. When the stud 61 passes the medial line of the bolt 50 and the stud 60, the spring 69 which has been placed under tension exerts a pull on the lever, thus causing it to rock on the roller 56 and force the 100 latch bill 42 over the end of the keeper 43, whereby the door is fully closed.

Normally the wings 24 and 28 of the carriage are spread apart, as is shown in dotted lines in Fig. 3, and the carriage is positioned on the track 10 so that as the elevator car travels up and down the shaft, the arms 48 and 49 pass between said wings but do not contact therewith. The wings are long enough to cause the arms to be positioned there-between when the car is stopped within the proper distance of the floor landing for opening the door. 105

Upon the initial movement of the carriage 21, the wing 24 engages the arm 48 and swings it into the arm 49, whereby the latch 41 is swung and the bill 42 is carried out of the path of the keeper 43, thereby releasing the door. Upon further movement of the carriage motion is contributed to the arm 49 110 and the opening movement of the door is started. The arm 36 of the bell crank lever 34 is in the path of the pin 37, which is located so as to be engaged by said arm upon the initial movement of the door, whereby the lever 34 is swung and the crank shaft 29 is rocked. Referring again to Fig. 3, it will be seen that when the shaft 29 is rocked the arm 31 and link 32 will be actuated to move 115 the slide 27, thus carrying the wing 28 into 120 the path of the pin 37. The door is held 125 open by the action of the lever 34 until the door is closed, at which time the door is held closed by the action of the lever 34 until the door is closed. 130

engagement with the arm 49, whereby the latch will be firmly held and the door properly opened.

The carriage is actuated by the chain 20 which is driven by the shaft 18 and sprocket 19. While any suitable means may be employed for driving the shaft 18, I prefer to connect a countershaft 64 therewith by a universal joint 65. This shaft 64 is suitably connected with the shaft 64' of a speed reduction device 66 of suitable construction. The speed reduction device is driven by an electric motor 67 (Figs. 7 and 8), which motor is rigidly attached to the said device, whereby these parts may be suspended as a unit. Brackets 68 are provided on the motor and on the device 66. Bolts 69 suspended from hangers 70 pass through these brackets which are sustained between coiled springs 71 and 72 suitably confined on said bolts.

By this means the motor and speed reduction device are resiliently suspended and vibration and noise are thus absorbed. Suitable rubber or felt washers may be used in connection with the springs or any other means employed to reduce the noise. The particular suspension means forms no part of this invention, as the motor may be suspended in any suitable way so long as provision is made for reducing the noise and vibration.

The standards 12 have vertical extensions 73 upon which is mounted an angle bar 74 above the chain 20, as is shown in Figs. 1, 2, 3, 4 and 22. To the rear side of this bar I secure a pair of air-check or cushioning cylinders 75 of the usual construction, each having a plunger 76. These plungers are directed towards each other and each is fastened to a carrier 77, as is best shown in Fig. 2. Each carrier includes a flanged roller 78 traveling on top of the bar 74 and a hanger 79 extending under said bar.

From each hanger a slide rod 80 extends toward one of the standards 12 and is supported in a guide 81 mounted on the bar 74. On the end of each rod is a guide lip 82 engaging over the flange of the bar 74 and a depending lug 83 having a button 84 on its rear side and a button 85 on its forward side, as is best shown in Fig. 3. On top of the carriage 21 is a small standard 85' having a plunger 86 mounted to slide therethrough. Coiled springs 87 are mounted on the plunger on each side of the standard and are confined by heads 88 on the ends of said plunger.

It will be seen that when the carriage 21 approaches either end of its stroke one of the heads 88 will engage the button 85 of one of the lugs 83, thus moving the rod 80 rearwardly and through the agency of the carrier 77 depressing the plunger 76 so as to cushion the same in the cylinder 75. This checks the movement of the door and cush-

ions the final movement, thus eliminating noise and shock.

In order to return the carrier 77 to its normal position upon the return stroke of the carriage 21, I provide on said carriage on each side of the spring plunger a pair of spring dogs 89, each having a laterally extending pin 90. By observing Fig. 3 it will be seen that when the carriage is moved to the left, the left hand dog 89 will ride under the lug 83 and catch under the button 84. As long as the plunger head contacts with the button 85 the dog will remain under the button 84. Upon the return stroke the pin 90 will engage a beveled deflector 91 which will depress the dog 89 on the left hand side (Fig. 3) and as the carriage continues to move to the right, the lug 83 will remain stationary and the plunger will be carried on by the carriage. This operation will be repeated at the opposite end of the stroke.

On the rear upper portion of the carriage I mount a pin 92, as is shown in Figs. 4, 5 and 6. On the angle bar 74 I mount a switch box 93 (Figs. 1, 2, 13 and 14). In this box is secured an insulating base plate 94 of fibre or other suitable material on which a contact 95 is secured. At the opposite end of the base another contact 96 is mounted. As is indicated from Fig. 16, each contact comprises a pair of spaced poles across which the circuit may be closed. On a transverse rock shaft 97 a switch bar 98 is fulcrumed. The bar is slotted to receive a pin 99 located between cross-pins 100 in the slotted portion of said bar. The pin 99 will engage one of the cross-pins when the shaft 97 is rocked and thus swing the bar down. This arrangement compensates wear and works in conjunction with swinging contact caps 101 carried by the ends of the bar and adapted to alternately engage the poles of the contacts 95 and 96 to bridge the circuits.

For swinging the bar 98 I mount a bell crank lever comprising arms 102 and 103 on the shaft 97 outside of the box. These arms are spaced apart and a coiled spring 104 has its lower end pivoted on a stud 104' midway between said arms. The upper end of the spring is pivotally suspended from a bracket 105 on top of the box. The lever is fastened on the shaft so that when the cap 101 is in engagement with the contact 95 the arm 103 will depend in the path of the pin 92 and the stud 104' will be to the left of the pivot of the lever, as is shown in Fig. 15. The spring exerting an upward pull will hold the parts in this position until they are reversed by the swinging of the lever, whereby the other contact 101 is engaged with the contact 96 and the arm 102 swung into the path of the pin 92. The poles of the contact 96 are connected with the car circuit and the poles 95 are connected with the door operating circuit.

130

At the other end of the bar 74 I mount a switch box 106 having an insulating base 107 on which is mounted a contact 108 comprising two poles and illustrated in Figs. 13 and 14. A rock shaft 109 is mounted in the box and a switch bar 110 is mounted thereon, the same as the switch bar 98. The switch bar carries a single contact cap 111 hinged thereon and adapted to engage the contact 108, which latter is connected with the reversing fields of the door operating motor 67.

A bell crank lever including arms 112 and 113 is fastened on the shaft outside of the box and has a stud 114 midway between the arms to which the lower end of a coiled spring 115 is pivoted. The upper end of the spring is pivotally suspended from a bracket 116 mounted on top of the box 106. 15 When the arm 112 is engaged by the pin 92 the shaft 109 is rocked to bring the cap 111 into engagement with the contact 108, thus closing the circuit, but when the arm 113 is engaged and swung by the pin the bar 110 20 will be raised as is shown in Fig. 13 and the circuit opened. The spring 115 will hold the lever arms in their adjusted positions.

In Fig. 21 I have shown a circuit diagram which includes the motor 67, the switch box 93 and the switch box 106. Main circuit wires A lead from the poles of the contact 96 to the elevator car operating motor (not shown) and constitute the power circuit. In order to control the operation of the 25 door circuit it is necessary to provide a master switch and a cutout switch, which are shown in Figs. 17, 18, 19 and 20.

The cutout switch comprises a box 117 mounted on one of the extensions 73 at the 30 end of the bar 74. This box has an insulating base 118 on which a contact 119, including spaced poles, is mounted. A crank shaft 120 is mounted in ears 121 on the outside of this box and has a crank arm 122 pivoted 35 to the upper end of a pitman 123 whereby it is operated. An arm 124 is secured at its upper end on the shaft 120 and has an extension 124' projecting into the box 117. A switch bar 125 is pivoted on the end of 40 this extension and carries a swinging cap 126 at its upper end adapted to engage the contact 119. A bell crank lever 127 is pivoted on the shaft 120 and swings between lugs 128 at the lower end of the arm 124. 45 A wire spring 129 having its upper end carried on the shaft 120 engages the lower end of the bell crank lever 127 and normally holds it against the outer lug 128. The shaft 120 is under the influence of a wire 50 spring 130 and the arm 124 is swung against the tension of said spring.

The lower end of the bell crank lever 127 is curved outwardly and forked for receiving a roller 131. Adjacent each floor landing 55 is a shoe 132 and normally the roller

passes this shoe without engaging it, but when the pitman 123 is pulled down to rock the shaft 120, the arm 124 swings the bell crank lever 127 so that the roller engages with the shoe, as is shown in dotted lines in Fig. 17. When the roller 131 engages the shoe, the lever 127 is swung relatively of the arm 124. A spring pressed plunger 133 in the upper end of the lever and within the box normally engages the bar 125 below 75 its pivot point, thus holding the cap 126 away from the contact 119, but when the lever is depressed as above described the point of the plunger rides along the bar 125 to a point above its center thus swinging 80 the bar, causing the cap 126 to engage the contact 119 and close the circuit.

At a suitable place in the car I mount the box 134 of the master switch. This box includes an insulating base 135 having a 85 series of contacts 136 on one side and a similar series 137 on the other side. At each end of the base I provide brackets 138 to which yoke members 138^a and 138^b are pivoted. A yoke bar 139 is fastened to the yoke members. 90 These members with the yoke bar are held in a central and neutral position by spring wires 140, as is shown in Fig. 18. A detent 141 mounted within the switch box extends through a slot 142 and has a handle 143. The inner end of this detent has swiveled connection with a bell crank lever 144 pivoted in the box and extending through a slot 145 in the base and back of the box. The outer end of this lever is pivoted to the 95 lower end of the pitman 123. The slot 142 has a guide 146 and the detent has a depending lug 147 for engaging this guide which limits the inward movement of the 100 detent and sustains it as it is swung to either side. When the detent is pushed in and 105 swung to one side, the lever 144 is operated to pull down the pitman 123.

The yoke 139 carries a plurality of spring 110 plunger contacts 148 adapted to engage with the contacts 136 or 137 when the bar is swung. These contacts are connected in common with a terminal 149 in the box 134. The contacts 136 are engaged when the detent is swung in one direction and the contacts 137 are engaged when the detent is swung in the opposite direction. A signal lamp 150 is mounted in the upper end of the box 134 and illuminates a lens 151 in the 115 top of said box.

Referring again to Fig. 21, an electric circuit supply wire B leads to one of the poles of the contact 119 of the cutout switch while a wire C leads from the other pole of said contact to the terminal 149 of the master switch. From this it will be seen that until the bell crank lever is operated, no current can pass to the master switch or the parts connected therewith. A circuit wire D leads 125 from the wire C to the socket of the lamp 130

150 and a return wire D¹ leads from said lamp to the first contact 137^a. A wire E leads from this contact to one of the poles of the contact 95 of the reversing switch. 5 Another wire E' leads from the other pole of said contact and forms the other side of the circuit, including the wire B. A branch wire F leads from the wire E' to one of the poles of the contact 108 of the opening switch, while wire G leads from the other pole of said contact to the first contact 136^a. Wires H, I, J and K lead from the remaining contacts 137 to the motor 67. The wires I and J are connected with the starting elements of the motor while the wires H and K are connected with the operating fields. The contact 137 of the wire K is bridged with the lower contact 136 by a wire M, while a wire N bridges the contacts 136^a and 137^a. 10 Crossed wires O bridge the contacts 137 connected with the wires I and J with the opposite contacts 136 for reversing the motor.

The operation is as follows:

The carriage 21 is normally at the right-hand end of the apparatus, reference being had to Figs. 1 and 2. Stop brackets 152 are provided at each end of the track to limit the travel of the carriage and said carriage will be in engagement with the bracket at the right-hand end when the device is not being operated. The switch arms 103 Fig. 15, and 112 Fig. 13, will be positioned as shown and in the path of the pin 92, Figs. 4, 5 and 6.

When it is desired to open the door the operator grasps the handle 143 and swings the detent 141 to the left (Figs. 17 and 21). This causes the bell crank lever 144 to be operated, whereby the pitman 123 is pulled downward and the arm 124 swung outwardly, thus positioning the roller 131 in the path of the shoe 132. The swinging of the arm and lever outwardly will not have any effect on the switch bar 125 except to lower it as is shown in dotted lines in Fig. 17.

40 When the roller rides onto the shoe 132, the lever 127 will be swung toward the switch box 117, as is shown in dotted lines in Fig. 17, whereby the plunger 133 will move up the rear edge of the bar 125 above the pivot point of the latter, thus swinging said bar and causing the cap 126 to engage the poles of the contact 119. The door operating circuit, which is normally open, is thus closed from the wire B through said contact and over wire C to the terminal 149 which is connected with the bracket 138 and the yoke member 138^a. The yoke member 138^a being engaged with the contacts 137 of the wires J and K provides for the passage of the current to the motor 67, while the yoke member 138^a being connected with the wires H and I provide a return passage from said motor. From the member 138^b circuit connection is made through the top contact 137^a, wire N 45 to the top contact 136^a, and thence over wire

G to one of the poles of the contact 108. The cap 111 being in engagement with said contact, the current will pass from the other pole over wire F to the wire E', thus completing the circuit.

70 The motor 67 thus being started will impart motion to the shaft 64' through the speed reduction device 66, whereby the shaft 64 will rotate the shaft 18 and the sprocket 19, thus causing the chain 20 and the carriage 21 to travel. When the elevator car is stopped, preparatory to opening the door, the arms 48 and 49 will stand between the shoes 24 and 28, the shoe 132 being located at such a point to bring about this relation. Upon the initial movement of the carriage the pin 37 (Fig. 6) will be engaged by the arm 36 of the bell crank lever 34, whereby said lever will be swung to rock the shaft 29. With reference to Figure 3, the shaft will 75 be rocked in a clock-wise direction thus swinging the arm 31 downwardly and by means of the link 32 moving the slide 27, whereby the wing 28 is carried toward the wing 24 as is indicated in full lines in Fig. 3.

80 This operation will cause the arm 48 to be pressed into the arm 49 against the tension of the spring 53, whereby the bill 42 of the latch 41 will be swung from the keeper 43, thus unlocking the door 47. As the carriage continues to move to the left (Figs. 1, 2 and 9) the lever 57 is swung about its pivot 50 until the lug 62 engages the pin 63 and the stud 61 is swung to the right of said pivot. This will bring the lever to the 85 position shown in dotted lines in Fig. 9, whereby its yoke 58 will be free to slide from the roller 56.

90 Also upon the initial movement of the carriage, the pin 92 (Figs. 4, 5 and 6) will engage the arm 102 (Figs. 15 and 16) and swing the bar 98 whereby the circuit connection with the contact 96 will be broken and circuit connection made with the contact 95. This will open the car circuit so that the car 95 can not be moved while the door is open. The closing of the circuit across the poles of the contact 95 will not have any effect until the master switch is operated to engage the contacts 136 and reverse the motor 67.

100 The carriage 21 continues to move to the left and open the door. When the door approaches the end of its opening stroke the operator swings the knob 143 to the center of the box to bring the bar 139 and its component parts to a neutral position. This will 105 swing the lever 127 and open the motor circuit.

110 As the carriage approaches the end of its opening stroke, the left-hand dog 89 (Figs. 1 and 3) will ride under the lug 83 and catch under the button 84. The left-hand head 88 of the plunger 86 will then engage the button 85 and this engagement will be cushioned 115 by the spring 86. As the carriage continues 120

to move the lug 83 will be carried to the left, thus sliding the rod 80 and pulling the left-hand carrier 74 (Fig. 2) to the left, whereby the plunger 76 is moved into the cylinder 75 and the movement of the carriage thus cushioned or checked. By the time the carriage strikes the left-hand stop 152, it will practically have completed its travel due to the checking action and the cutting off of the motor circuit. Consequently, the door will be brought to a stop quite and all noise will practically be eliminated.

As the carriage approaches the end of its opening stroke, the pin 92 will engage the arm 113 of the switch box 106 and swing the shaft 109, whereby the switch bar 110 will be swung to position shown in Fig. 13. This will break the circuit across the poles of the contact 108 and stop the motor 67 if the operator should fail to move the bar 139 to a neutral position.

When it is desired to close the door, the handle 143 will be swung to the right (Figs. 17 and 21). This will cause the contacts 148 to engage the contacts 136 and 136^a. Owing to the crossed wires O the wire J will be connected with the contact 137 engaged with the yoke member 138^a instead of the wire J and this will reverse the motor because the current will flow from the wire C over the wire I instead of over the wire J. The return from the wire J will be carried by one of the wires O to the contact 136, which is engaged by the yoke member 138^b and the circuit will be completed over the wires N and E, contact 95 and wire E'.

When the carriage starts on its closing stroke, the pin 92 will engage the arm 112 and swing the switch bar 110 to engage the cap 111 with the contact 108, thus restoring the circuit which was opened at the end of the opening stroke. The left-hand dog 89 (Fig. 3) still being in engagement with the lug 83 will move the said lug and the rod 80 to the right, thus pulling the plunger 76 from the cylinder 75. By the time the plunger has been pulled to its outward limit, the pin 90 of said dog will ride under the deflector 91, whereby the dog will be disengaged from the lug 83 and further movement of the rod 80 of the left-hand check prevented.

As the carriage approaches the end of its closing stroke the right-hand dog 89 (Figs. 1 and 3) will ride under the lug 83 of the right-hand check whereby the head 88 on the right-hand end of the plunger 86 will engage said lug, which action will be cushioned by the spring 87. This will cushion the closing movement of the door as will be obvious.

As the carriage approaches the end of its closing stroke the pin 92 will engage the arm 103 (Figs. 1, 15 and 16) and swing the switch bar 98, whereby the circuit across the poles

of the contact 95 will be broken and the car circuit across the poles of the contact 96 will be closed. At the same time the arm 35 (Fig. 6) of the lever 34 will engage the pin 37 whereby the shaft 29 will be rocked to operate the slide 27 and spread the wings 24 and 28.

The spreading of the wings of the shoe will permit the spring 53 to swing the latch 41 so that the bill 42 (Fig. 9) may ride over the beveled end of the keeper 43 and thus latch the door. As the door approaches its closing position, the yoke 58 engages the roller 56 and the lever is thus fulcrumed on the roller and swung as the door moves toward the end of its closing stroke. As soon as the stud 61 passes the center of the pivot 50 the spring 59 will exert a pull on the lever and thus continue to swing said lever whereby the door will be impelled to a fully closed position, even though it has lost momentum by the stopping of the motor 67.

When the door is closed, or just previous to its closing, the operator swings the bar 139 to a neutral position, thus opening all circuits through the master switch. This also swings the arm 124 and the lever 127 to their normal position, whereby the plunger 133 swings the bar 125 and breaks the circuit by moving the cap 126 from the contact 119.

What I claim, is:

1. In an elevator door operating apparatus, means located at the door for opening and closing the same, electrically operated means carried by the car and located to engage the door actuating means at the floor landing only, the electrical circuit of the operating means being normally open, means for closing said circuit when the operating means engages the door actuating means, and a cushion device engaged by the electrically operated means carried by the car.

2. In an elevator door operating apparatus, means located at the door for opening and closing the same, electrically operated means carried by the car and located to engage the door actuating means at the floor landing only, the electrical circuit of the operating means being normally open, means for closing said circuit when the operating means engages the door actuating means, means actuated by the operating means for breaking the power circuit to the car when the doors are opened, and a cushion device engaged by the electrically operated means carried by the car.

3. In an elevator door operating apparatus, means located on the floor landing door for opening and closing the same, electrically operated means carried by the car and located to engage the door actuating means at the floor landing only, the electrical circuit of the operating means being normally open, a cut-out switch carried by the car and connected in said circuit, means at each floor

for operating said cut-out switch, and a master switch for the said electrical circuit including means for setting the cut-out switch for operation.

5. In an elevator door operating apparatus, means located on the floor landing door for opening and closing the same, electrically operated means carried by the car and located to engage the door actuating means at the floor landing only, the electrical circuit of the door operating means being normally open, a normally open cut-out switch carried by the car and connected in said circuit, means at each floor for operating said cut-out switch, a master switch for the said electrical circuit including means for setting the cut-out switch for operation by said floor operating means, a circuit controlling switch carried by the car and normally closing the car power circuit, and means set to operate by the door operating means upon its initial movement to engage the controlling switch operating means for actuating said controlling switch to open the power circuit.

6. In an elevator door operating apparatus, means located on the floor landing door for opening and closing the same, electrically operated means carried by the car and located to engage the door actuating means at the floor landing only, the electrical circuit of the door operating means being normally open, a normally open cut-out switch carried by the car and connected in said circuit, means at each floor for operating said cut-out switch, a master switch for the said electrical circuit including means for setting the cut-out switch for operation by said floor operating means, a circuit controlling switch carried by the car and normally closing the car power circuit, means set to operate by the door operating means upon its initial movement to engage the controlling switch operating means for actuating said controlling switch to open the power circuit, and a motor circuit contact carried by said controlling switch and closed when said switch is operated to break said power circuit, whereby said operating circuit of the door operating means is closed through said switch.

7. In an elevator door operating apparatus, means on the floor landing door for opening and closing the same, a traveling carriage mounted on the car and having a shoe for engaging said door opening and closing means, electrically operated means for operating said carriage, a pair of cushions, means for operating said cushions engaged by the carriage at each end of its travel, and means on the carriage for restoring said cushion operating means to its normal position.

8. In an elevator door operating apparatus, a door actuating member movably

mounted on the elevator car, means for operating said means, a door latch on each floor landing door and having an actuating arm for engagement by the actuating member, a door closing lever carried by the latch, a relatively stationary fulcrum engaged by the said lever, and means for operating said lever.

8. As a sub-combination in an elevator door operating apparatus, a floor landing door latch having an actuating arm, a relatively stationary arm carried by the door adjacent the latch arm, said arms being engaged by door actuating means carried on the elevator car, a fulcrum on the wall of the elevator shaft, a lever pivoted on the latch and having a yoke for engaging the fulcrum, and a spring means attached to the latch and lever on opposite sides of the pivot of the lever for swinging said lever on the fulcrum.

9. In an elevator door operating apparatus, a longitudinal track, a carriage reciprocating on said track and having a door actuating shoe, means for reciprocating said carriage, means for opening and closing said shoe, a pair of air cushion cylinders, a support for said cylinders, operating members connected with the plungers of said cylinders, a spring plunger carried by the carriage for engaging one of said operating members at each end of its stroke, and means on the carriage for restoring said operating members to their normal positions.

10. In an elevator door operating apparatus, a door opening and closing member, a motor for operating said member, an electrical circuit controlling said motor, a cut-out switch connected in said circuit, a circuit opening and closing member in said switch, an operating lever for said switch member, a shoe for actuating said operating member, and means for positioning said lever in the path of said shoe.

11. In an elevator door operating apparatus, a door opening and closing member, a motor for operating said member, an electrical circuit controlling said motor, a cut-out switch connected in said circuit, a circuit opening and closing member in said switch, an operating lever for said switch member, a shoe for actuating said operating member, means for positioning said lever in the path of said shoe, a master switch connected in said motor circuit and including an operating element, and a connection between said operating element of the master switch and the said positioning means for operating the latter.

12. In an elevator door operating apparatus, the combination of door operating means carried by the floor landing door, a track, a carriage mounted to travel on said track, a shoe wing stationary on said carriage, a member movable on said carriage

and carrying a shoe wing, a crank shaft mounted in the carriage, a connection between the crank shaft and the movable member, a lever mounted on the crank shaft and having spaced arms, a coiled spring for holding said lever in position, and means for automatically swinging said lever when the carriage is moved.

13. In an elevator door operating apparatus, a door opening and closing member, a motor for operating said member, an electrical circuit controlling said motor, a cutout switch connected in said circuit, a circuit opening and closing member in said cutout switch, a lever mounted on said switch and carrying said circuit opening and closing member, an arm pivoted on said switch adapted to engage said member, a spring connecting the arm and the lever, a roller carried by the arm, a shoe engaged by the roller, and means for swinging the lever and the arm to position the roller in the path of the shoe.

14. In an elevator door operating apparatus, a door opening and closing member, a motor for operating said member, an electrical circuit controlling said motor, a cutout switch connected in said circuit, a circuit opening and closing member in said cutout switch, a lever mounted on said switch and carrying said circuit opening and closing member, an arm pivoted on said switch adapted to engage said member, a spring connecting the arm and the lever, a roller carried by the arm, a shoe engaged by the roller, a master switch electrically connected with the cutout switch and including a mov-

able actuating member, and an operating connection between the said switch actuating member and the lever for swinging the latter.

15. In an elevator door operating apparatus, means on the floor landing door for opening and closing the same, a traveling carriage mounted on the elevator car and having a vertical shoe for receiving said door operating means, electrically operated means for operating said carriage, a circuit cutout switch connected in the circuit of said electrically operated means, a movable member for operating the cutout switch, and an actuating shoe for said member located in the elevator shaft having an actuating surface of such length as to be engaged by the switch operating member only while the door opening and closing means is within the shoe of the travelling carriage.

16. In an elevator door operating apparatus, a longitudinal track, a sprocket wheel mounted at one end of the track, a drive shaft at the opposite end of the track, a friction clutch connected to said shaft, a drive sprocket connected with said clutch, an endless chain travelling around and between said sprockets, a carriage slideable on the track and attached to the chain, air cushion cylinders mounted in opposed relation and having plungers, resiliently sustained actuating means carried by the carriage, operating members connected with the plungers and individually engaged by the actuating means at each end of the stroke of the carriage.

In testimony whereof I affix my signature.
OSCAR P. McGEE.
